PANEL FASTENING ELEMENT

Anders C. Olsen, Forest Hills, N. Y.

Application April 13, 1943, Serial No. 482,854

7 Claims. (Cl. 24—81)

This invention relates to building structures and particularly to interior partition, wall and ceiling constructions.

More particularly, the invention is concerned with partition and like structures wherein paneling—such as paneling composed of plasterboard known as gypsum lath, or of relatively soft and porous fiberboard known as insulating lath—is used as a base for the application of the plaster to form a partition or ceiling.

In order that the erection of partitions embodying such panel lathing be more convenient and economical, and the finished partitions be more durable in service, the present invention contemplates the provision of a novel connection between the panel lathing which meet at an angle, such as at the corners of a room between intersecting walls or partitions. More particularly, it is an object of the invention to provide a novel clip or securing element which is adapted to engage and interconnect the adjacent margins of the paneling or lathing elements meeting at such corners, and to firmly but resiliently maintain the proper angular position between the panels at the meeting corner, without requiring the use of other reinforcement.

Other objects and features of the invention will be more clearly apparent from the detailed description which is to follow and from the drawing in which:

Fig. 1 is a fragmentary view in perspective of an interior corner of a room, utilizing the corner fastening means of the present invention;

Fig. 2 is a view in horizontal cross-section taken substantially on line 2—2 of Fig. 1, and

Fig. 3 is an enlarged view in perspective of a corner fastening element embodying the present invention.

The view in Fig. 1 of the drawing shows the corner of an interior construction in which the plastering lath panels 10 and 11 respectively of partitions A and B meet at right angles. In the type of partition construction herein selected for illustration purposes, the panels 10 and 11, along with the other panels (not shown) comprising the plastering bases, are each considerably longer than its width and of a length approximately equal to the height of the partition.

In order to maintain the proper angular position between the panels 10 and 11 at the meeting corner, and firmly to retain them in such position, the adjacent edges of these panels are interconnected by means of the novel corner clip designated generally by the numeral 20. This clip 20 preferably is made of a single piece of

hard drawn wire, of say 11 to 14 gauge, which is bent to form a pair of open loops 21 and 22 extending substantially in parallel spaced planes and another similar pair of open loops 23 and 24 extending in substantially parallel spaced planes, at right angles to the planes of the first-named pair.

As will be noted, the leg 31 of the outer loop 21 terminates inwardly of the corresponding end 10 of the leg 25 and joins the leg 32 of the inner loop 24 at the right angular bend 33. Likewise, the leg 29 of loop 24 terminates inwardly of the corresponding end of leg 32 and joins leg 28 of the inner loop 22 at the right angular bend 30. The right angular bend 27 where the leg 25 of outer loop 21 joins the leg 26 of outer loop 23 lies at a point offset outwardly with respect to the bends 30 and 33.

The leg 34 is somewhat shorter than the other leg 28 of the loops 22; and similarly, the leg 35 is somewhat shorter than the leg 26 of loop 23. The leg 34 has a sharpened prong end 36 and the leg 35 has a similar pronged end 37. The pronged end 36 extends outwardly slightly from the plane of the loop 22 toward the plane of the loop 21 and the pronged end 37 extends inwardly slightly from the plane of the loop 23 toward the plane of the inner loop 24.

The application of the clips 20 for the purpose of interconnecting the adjacent edges of the panels 10 and 11 meeting at a corner, and, thereby, dispensing with the need for using corner studs, or other corner supporting members, is clearly shown in Fig. 1. As shown, each of the clips 30 is first engaged with the panel 10 of partition A by sliding the clip laterally over the edge of the panel until the leg 25 of the outer loop 21 butts up against this edge, and the opposite panel surfaces 40 and 41 are firmly gripped or embraced between the spaced loops 23 and 24 for the full lengthwise extent of the loops. In thus applying the clips individually, a slight amount of pressure is required to deflect or spring the spaced loops 23 and 24 of each clip out of their normal planes sufficiently to embrace the margins of the opposite panel surfaces 40 and 41. The flexing of the resilient legs of the loops from their normal substantially unflexed position to the position where the loops 23 and 24 bear upon the 35 opposite panel surfaces, serves firmly to grip the panel. Each of the clips are separately applied in this manner and are suitably spaced approximately 16" apart along the vertical edge of the panel 10.

When the required number of clips 20 have

thus been affixed along the edge of panel 10, the panel 11 of the partition B is moved into right angular position adjacent the panel 10, the edge of the panel 11 being forcibly inserted between the extended spaced loops 21 and 22 of each of the clips 20, and the margins of the panel surfaces 42 and 43 being firmly embraced by the loops bearing thereagainst.

While the gripping pressure exerted by the spaced loops of each clip against the opposite faces of the meeting panels is usually sufficient alone to maintain the clip in fixed engagement with the panels, the pronged ends 36 and 37 provide positive means for resisting outward displacement or slippage of the clips. As shown in Fig. 2, the pronged end 37 of the outer loop 23 is embedded in the surface 40 of panel 10 and the pronged end 36 of the inner loop 22 is likewise embedded in the inner surface 43 of panel 11. The extent to which these prongs pierce the panel surfaces is somewhat exaggerated in the drawing for purposes of illustration, it being understood that it is only necessary for the prongs to slightly rupture the panel surfaces in order to offer sufficient resistance to any relative movement between the clips and the panels which would tend to release the firm, fixed engagement therebetween.

It is thus apparent that the clips of the present invention not only serve adequately to interconnect the adjacent panels meeting at a corner and to provide firm positioning of the panels along the vertical joint, but also maintain the proper angular position between the panels without requiring the use of additional supporting means. The resiliency of the clips, as previously indicated, permits a considerable range of flexure adequate to grip and interconnect panels ranging from $\frac{3}{8}$ " to $\frac{1}{2}$ " in thickness, where the distance between the spaced loops of each pair is approximately $\frac{3}{8}$ ". By forming the clips so that the distance between the spaced loops is approximately $\frac{3}{4}$ ", they may be used for connecting panels of $\frac{3}{4}$ " to 1" thickness, as for example, in the case of insulation lath. The rapidity and ease with which corner panels may be engaged and interconnected with these clips speeds up the erection of the partition or wall and, thereby, produces a definite saving in time and labor.

After the plastering bases have been properly installed, the partitions are finished by applying desired thicknesses of plaster to both sides of the plastering bases.

The clips rigidify the partition structure both vertically and horizontally by reason of their gripping action on the margins of the panels along the vertical joint. At the same time, the clips serve automatically to space one panel from the intersecting panel a distance equal to the thickness of the material from which the clips are made, thereby permitting the plaster to key through this space. Moreover, since the clips protrude beyond the panel surfaces, they thereby provide an enhanced key effect for the plaster coating.

While the clips embodying the present invention have been described in connection with studless partitions employing panels each extending for the full height of the partition, it is also within the purview of the invention to apply these clips along the vertical joint between intersecting panels of less length than the height of a partition, or along the horizontal joints between the intersecting panels of a partition

and a ceiling structure, when such partitions are erected on studs, channels or other vertical supports.

I claim:

5. 1. As an article of manufacture, a clip for use in connecting the edges of a pair of plastering lath panels which are in juxtaposition to one another in planes extending at right angles to one another, said clip comprising a single piece of resilient wire bent to form a pair of open loops extending substantially in parallel spaced planes and another pair of open loops extending in substantially parallel spaced planes at right angles to the planes of the first-named pair, each of said pairs of spaced loops being formed to grip therebetween the margins of one of the panels along the joint between the panels.
10. 2. As an article of manufacture, a clip for use in connecting the edges of a pair of plastering lath panels which are in juxtaposition to one another in planes extending at right angles to one another, said clip comprising a single piece of resilient wire bent to form a pair of open loops extending substantially in parallel spaced planes and another pair of open loops extending in substantially parallel spaced planes at right angles to the planes of the first-named pair, each of said pairs of spaced loops being formed to grip therebetween the margins of one of the panels along the joint between the panels, one of the loops of said spaced pairs being provided with means for engaging a surface of the panel clampingly embraced therebetween.
15. 3. As an article of manufacture, a clip for use in connecting the edges of a pair of plastering lath panels which are in juxtaposition to one another in planes extending at right angles to one another, said clip comprising a single piece of resilient wire bent to form a pair of open loops extending substantially in parallel spaced planes and another pair of open loops extending in substantially parallel spaced planes at right angles to the planes of the first-named pair, each of said pairs of spaced loops being formed to grip therebetween the margins of one of the panels along the joint between the panels, one of the loops of each said spaced pairs being provided with means for engaging a surface of the panel clampingly embraced therebetween.
20. 4. As an article of manufacture, a clip for use in connecting the edges of a pair of plastering lath panels which are in juxtaposition to one another in planes extending at right angles to one another, said clip comprising a single piece of resilient wire bent to form a pair of open loops extending substantially in parallel spaced planes and another pair of open loops extending in substantially parallel spaced planes at right angles to the planes of the first-named pair, each of said pairs of spaced loops being formed to grip therebetween the margins of one of the panels along the joint between the panels, one of the loops of each said spaced pairs terminating in a pronged end adapted to engage the adjacent surface of the panel gripped between each of said pairs of loops.
25. 5. As an article of manufacture, a clip for use in connecting the edges of a pair of plastering lath panels which are in juxtaposition to one another in planes extending at right angles to one another, said clip comprising a single piece of resilient wire bent to form a pair of open loops extending substantially in parallel spaced planes and another pair of open loops extending in substantially parallel spaced planes at right angles to the planes of the first-named pair, each of said pairs of spaced loops being formed to grip therebetween the margins of one of the panels along the joint between the panels, one of the loops of each said spaced pairs terminating in a pronged end adapted to engage the adjacent surface of the panel gripped between each of said pairs of loops.
30. 6. As an article of manufacture, a clip for use in connecting the edges of a pair of plastering lath panels which are in juxtaposition to one another in planes extending at right angles to one another, said clip comprising a single piece of resilient wire bent to form a pair of open loops extending substantially in parallel spaced planes and another pair of open loops extending in substantially parallel spaced planes at right angles to the planes of the first-named pair, each of said pairs of spaced loops being formed to grip therebetween the margins of one of the panels along the joint between the panels, one of the loops of each said spaced pairs terminating in a pronged end adapted to engage the adjacent surface of the panel gripped between each of said pairs of loops.
35. 7. As an article of manufacture, a clip for use in connecting the edges of a pair of plastering lath panels which are in juxtaposition to one another in planes extending at right angles to one another, said clip comprising a single piece of resilient wire bent to form a pair of open loops extending substantially in parallel spaced planes and another pair of open loops extending in substantially parallel spaced planes at right angles to the planes of the first-named pair, each of said pairs of spaced loops being formed to grip therebetween the margins of one of the panels along the joint between the panels, one of the loops of each said spaced pairs terminating in a pronged end adapted to engage the adjacent surface of the panel gripped between each of said pairs of loops.
40. 8. As an article of manufacture, a clip for use in connecting the edges of a pair of plastering lath panels which are in juxtaposition to one another in planes extending at right angles to one another, said clip comprising a single piece of resilient wire bent to form a pair of open loops extending substantially in parallel spaced planes and another pair of open loops extending in substantially parallel spaced planes at right angles to the planes of the first-named pair, each of said pairs of spaced loops being formed to grip therebetween the margins of one of the panels along the joint between the panels, one of the loops of each said spaced pairs terminating in a pronged end adapted to engage the adjacent surface of the panel gripped between each of said pairs of loops.
45. 9. As an article of manufacture, a clip for use in connecting the edges of a pair of plastering lath panels which are in juxtaposition to one another in planes extending at right angles to one another, said clip comprising a single piece of resilient wire bent to form a pair of open loops extending substantially in parallel spaced planes and another pair of open loops extending in substantially parallel spaced planes at right angles to the planes of the first-named pair, each of said pairs of spaced loops being formed to grip therebetween the margins of one of the panels along the joint between the panels, one of the loops of each said spaced pairs terminating in a pronged end adapted to engage the adjacent surface of the panel gripped between each of said pairs of loops.
50. 10. As an article of manufacture, a clip for use in connecting the edges of a pair of plastering lath panels which are in juxtaposition to one another in planes extending at right angles to one another, said clip comprising a single piece of resilient wire bent to form a pair of open loops extending substantially in parallel spaced planes and another pair of open loops extending in substantially parallel spaced planes at right angles to the planes of the first-named pair, each of said pairs of spaced loops being formed to grip therebetween the margins of one of the panels along the joint between the panels, one of the loops of each said spaced pairs terminating in a pronged end adapted to engage the adjacent surface of the panel gripped between each of said pairs of loops.
55. 11. As an article of manufacture, a clip for use in connecting the edges of a pair of plastering lath panels which are in juxtaposition to one another in planes extending at right angles to one another, said clip comprising a single piece of resilient wire bent to form a pair of open loops extending substantially in parallel spaced planes and another pair of open loops extending in substantially parallel spaced planes at right angles to the planes of the first-named pair, each of said pairs of spaced loops being formed to grip therebetween the margins of one of the panels along the joint between the panels, one of the loops of each said spaced pairs terminating in a pronged end adapted to engage the adjacent surface of the panel gripped between each of said pairs of loops.
60. 12. As an article of manufacture, a clip for use in connecting the edges of a pair of plastering lath panels which are in juxtaposition to one another in planes extending at right angles to one another, said clip comprising a single piece of resilient wire bent to form a pair of open loops extending substantially in parallel spaced planes and another pair of open loops extending in substantially parallel spaced planes at right angles to the planes of the first-named pair, each of said pairs of spaced loops being formed to grip therebetween the margins of one of the panels along the joint between the panels, one of the loops of each said spaced pairs terminating in a pronged end adapted to engage the adjacent surface of the panel gripped between each of said pairs of loops.
65. 13. As an article of manufacture, a clip for use in connecting the edges of a pair of plastering lath panels which are in juxtaposition to one another in planes extending at right angles to one another, said clip comprising a single piece of resilient wire bent to form a pair of open loops extending substantially in parallel spaced planes and another pair of open loops extending in substantially parallel spaced planes at right angles to the planes of the first-named pair, each of said pairs of spaced loops being formed to grip therebetween the margins of one of the panels along the joint between the panels, one of the loops of each said spaced pairs terminating in a pronged end adapted to engage the adjacent surface of the panel gripped between each of said pairs of loops.
70. 14. As an article of manufacture, a clip for use in connecting the edges of a pair of plastering lath panels which are in juxtaposition to one another in planes extending at right angles to one another, said clip comprising a single piece of resilient wire bent to form a pair of open loops extending substantially in parallel spaced planes and another pair of open loops extending in substantially parallel spaced planes at right angles to the planes of the first-named pair, each of said pairs of spaced loops being formed to grip therebetween the margins of one of the panels along the joint between the panels, one of the loops of each said spaced pairs terminating in a pronged end adapted to engage the adjacent surface of the panel gripped between each of said pairs of loops.
75. 15. As an article of manufacture, a clip for use in connecting the edges of a pair of plastering lath panels which are in juxtaposition to one another in planes extending at right angles to one another, said clip comprising a single piece of resilient wire bent to form a pair of open loops extending substantially in parallel spaced planes and another pair of open loops extending in substantially parallel spaced planes at right angles to the planes of the first-named pair, each of said pairs of spaced loops being formed to grip therebetween the margins of one of the panels along the joint between the panels, one of the loops of each said spaced pairs terminating in a pronged end adapted to engage the adjacent surface of the panel gripped between each of said pairs of loops.

angles to the planes of the first-named pair, each of said pairs of spaced loops being formed to grip therebetween the margins of one of the panels along the joint between the panels, one of the loops of each said spaced pairs terminating in a pronged end adapted to engage the adjacent surface of the panel gripped between each of said pairs of loops, each prong extending in a direction toward the other loop of said pair.

6. As an article of manufacture, a clip for use in connecting the edges of a pair of plastering lath panels which are juxtaposition to one another in planes extending at right angles to one another, said clip comprising a single piece of resilient wire bent to form a pair of open loops extending substantially in parallel spaced planes and another pair of open loops extending in substantially parallel spaced planes at right angles to the planes of the first-named pair, each of said pairs of spaced loops being formed to grip therebetween the margins of one of the panels along the joint between the panels, one leg of a loop of one pair being connected at right angles to one leg of a loop of the other pair.

7. As an article of manufacture, a clip for use in connecting the edges of a pair of plastering lath panels which are in juxtaposition to one another in planes extending at right angles to one another, said clip comprising a single piece of resilient wire bent to form a pair of open loops extending substantially in parallel spaced planes and another pair of open loops extending in substantially parallel spaced planes at right angles to the planes of the first-named pair, each of said pairs of spaced loops being formed to grip therebetween the margins of one of the panels along the joint between the panels, one leg of a loop of one pair being connected at right angles to one leg of a loop of the other pair, the outer loop of said first-named pair and the inner loop of said latter-named pair each terminating in a pronged end adapted to engage the adjacent surface of the panel gripped between each pair of inner and outer loops.

ANDERS C. OLSEN.
